[57] CLAIM

The ornamental design for a display device, as shown and described.

DESCRIPTION

FIG. 1 is a perspective view showing the top and two faces of a display device according to my new design; FIG. 2 is a top view of the display device shown in FIG. 1;

FIG. 3 is an elevation showing a side of the display device shown in FIG. 1, the other two sides being identical thereto; and,

FIG. 4 is a bottom view of the display device shown in FIG. 1.

FIG. 1

FIG. 2

FIG. 3

FIG. 4
